UNITED STATES PATENT OFFICE.

EUGENE I. BLOUNT, OF EVERETT, MASSACHUSETTS, ASSIGNOR OF ONE-HALF
TO THEOPHILUS KING, OF BOSTON, MASSACHUSETTS.

DOOR-CHECK.

SPECIFICATION forming part of Letters Patent No. 685,708, dated October 29, 1901.

Application filed September 21, 1896. Serial No. 606,533. (No model.)

To all whom it may concern:

Be it known that I, EUGENE I. BLOUNT, of Everett, in the county of Middlesex and State of Massachusetts, have invented certain new and useful Improvements in Door-Checks, of which the following is a specification.

This invention has for its object the production of a novel door-check; and it consists in the novel features of construction and relative arrangement of parts hereinafter fully described in the specification, clearly illustrated in the drawings, and particularly pointed out in the claims.

Reference is to be had to the accompanying four sheets of drawings, forming a part of this application, in which like characters indicate like parts wherever they occur.

Figure 1 represents a front elevation of my check mounted in position on the door. Fig. 2 represents a top plan view of the same. Fig. 3 is a vertical sectional view on the line 3 3 of Fig. 2. Fig. 4 is a cross-sectional view on the line 4 4 of Fig. 3, taken so as to show the manner of connecting the ends of the spring and the parts to which they are attached. Fig. 5 is a view similar to Fig. 4, showing the spring reversed. Fig. 6 represents a cross-sectional view on the line 6 6 of Fig. 3. Fig. 7 is a detail view of a portion of the mechanism illustrated in Fig. 6, showing the dog reversed. Fig. 8 is a cross-sectional view on the line 8 8 of Fig. 3, taken to show the weights in plan view. Fig. 9 is a bottom plan view of the part shown in Fig. 3 with the lower cap removed. Fig. 10 represents in front elevation the operative parts of the check, spring, and casing shown in section. Fig. 11 represents a view showing the weights and their rings, the rings and portion of the casing and cap being shown in section. Fig. 12 represents a top plan view of the pinion and ring, the arms of the weights being shown in section. Fig. 13 represents a perspective view of the pinion and the parts carried thereby. Fig. 14 represents a perspective view showing the weights mounted in position in the arms carried by the pinion. Fig. 15 is a perspective view of the main arbor or shaft with the collar supporting the dog. Fig. 16 represents a detail view of means for preventing the non-

operative movements of the weights. Fig. 17 is a detailed view of the brake-shoe. Figs. 18 and 19 represent views similar to Fig. 6, showing a different form of dog and clutch mechanism. Fig. 20 represents a cross-sectional view on line 20 20 of Fig. 10, showing in plan view a different form of friction and weights. Fig. 21 represents a front elevation thereof, the casing being shown in section. Fig. 22 is a cross-sectional view on line 22 22 of Fig. 20, showing the spring connections for the friction. Fig. 23 is a view similar to Fig. 20, showing another form of weight and friction device. Fig. 24 represents a vertical sectional view thereof on line 24 24 of Fig. 23, showing the construction of the pinion and the manner of connecting the weights therewith. Fig. 25 is a cross-sectional view on line 25 25 of Fig. 23, showing the construction of the weights and frictions and the manner of connecting the weights together.

Referring to the drawings, in the embodiment of my invention therein shown and selected by me for the purpose of illustrating my invention *a* represents a casing comprising a spring barrel-chamber *b*, closed by a cap *e*, pressed on said casing, and a cylindrical box or chamber *c*, having an extension *d*, both designed to contain gearing and the parts operated thereby. The open end of the chamber *c* is closed by a cap *f*, screw-threaded thereon, as shown, the several parts of the casing as described being further clearly shown in Figs. 3 and 10. The casing is secured to the door by means of screws *t*, passing through brackets *u*, extending out therefrom.

g represents a shaft or arbor arranged in said casing, its lower end arranged in an opening *f*, formed in an extension *f*² of the cap *f*. The upper end of the shaft *g* passes through a sleeve *i*, arranged in cap *e*. This sleeve is formed at its upper end with a ratchet-wheel *j*, the latter having an annular groove *k*, constructed to receive a complementary flange *l* on the top of the plate *e* and surrounding the sleeve *i*.

The portion of the shaft *g* that projects beyond the sleeve *i* is reduced, as shown in Figs. 3, 10, and 15, to enter an elongated slot in

the end of the lever m . The free end of this lever is connected to a stationary bracket n on the door-frame by a link consisting of a threaded rod n' , fitted in said bracket and having its opposite end threaded into a turn-buckle m' . This buckle is split at its upper end to hold between its split portion a spherical head m^2 of a pin projecting from the free end of the lever m . The split portions m^3 of the turnbuckle are clamped together by a screw m^4 . The turnbuckle may be removed from the pin m^2 and may be adjusted along the rod n' in either direction by loosening the screw m^4 , after which it may be again clamped to the pin m^2 by tightening said screw.

In the chamber b of the casing I place a spiral spring v of any desired degree of strength. The outer end w of this spring is bent, as shown in Figs. 4 and 5, to engage a portion of the edge of the casing, which is apertured for this purpose, the inner end of the spring being bent and inserted in a slot i' of the sleeve i . A dog x is pivoted upon the under side of the lever m , as shown in dotted lines in Fig. 2, and arranged to engage the teeth of the ratchet-wheel j . The parts are so constructed and arranged that the dog x engages the teeth of the ratchet-wheel when the door is being opened, causing the rotation of the sleeve i and the winding up of the spring v . The power stored up by the spring by the opening of the door acts upon the sleeve and the parts operated thereby to close the door. If the spring were left to its independent action, it would cause the door to close with a slam. To prevent this and to cause the door to close as slowly and noiselessly as desired, I employ self-regulating controlling or checking devices, which I will now proceed to describe.

On the shaft g is rigidly secured a collar y , having a socket y' to receive the circular end z' of a dog z , the outer end of which may be serrated, as in Figs. 6 and 7, at z^2 to engage the internal teeth d' of the wheel d , that is loosely mounted upon the shaft g and formed with external teeth d^2 . The wheel d is supported by an interrupted ring x' , secured to the internal walls of the casing and extending partially around the same. The shaft g is supported by a collar g' , preferably integral with a web g^2 , extending from the casing. (See Fig. 15.) The dog z is normally held in engagement with the internal teeth d' by means of a spring z^3 and is so arranged that when the shaft is rotated in one direction the dog will slide relatively with the wheel d ; but when the pressure or power stored up in the spring v causes the shaft to rotate in the opposite direction the dog z , in the form shown in Figs. 6 and 7, will engage the rack-teeth d' of the ratchet-wheel and rotate it.

The external teeth d^2 of the wheel d mesh with the pinion d^3 , fast on the shaft d^4 , journaled in the extension d^5 . A gear d^6 , also fast on the shaft d^4 and arranged under the wheel d , meshes with the teeth d^7 of the pin-

ion-sleeve d^8 , loosely mounted on the shaft g and arranged to slide thereon. (See Figs. 3, 10, 11, 13, and 14.)

The pinion-sleeve d^8 is formed at its lower end with radial arms d^9 , carrying at their outer ends a ring d^{10} , which is approximately equal in diameter to the interior of the lower chamber c of the casing. In the ends of the arms d^9 are formed apertures d^{11} to receive arms d^{12} , connected to and carrying governor-weights d^{14} . (See Figs. 3, 8, 9, 10, 11, 12, 13, 14, and 17.) Three of these weights are shown; but the number can be varied as desired. Each weight in the form shown in the figures referred to is sector-shaped in horizontal section, and the three weights employed form a circle in plan view, as illustrated in Fig. 8. The pinion-sleeve rests upon and is supported by an annular ring f^4 , forming a continuation of the walls of the opening f' in the extension f^2 . (See Figs. 3 to 21.) This pinion-sleeve at its lower end may be formed as shown in Fig. 11, or it may be cored out, as shown in Fig. 24, this cored-out or recessed portion d^{21} being arranged to surround the ring f^4 , the top of the ring engaging the step d^{22} , of leatheroid or other suitable material.

The arm d^{12} of each weight is pivoted by a pin d^{15} in the apertures d^{11} . Each arm d^{12} carries a finger d^{16} , adapted to engage a friction-ring r , arranged in the bottom of the chamber c of the casing, when the weights are thrown out, as hereinafter described. The ends of the fingers d^{16} extend into the space between the friction-ring r and the ring d^{10} . (See Fig. 11.)

r' is a friction-ring arranged above the ring d^{10} and separated therefrom by a washer r^2 . The ring r' is prevented from moving away from the ring d^{10} by a lip c' on the interior wall of the casing. (See Figs. 3 and 11.) The pivots d^{15} of the arms d^{12} are so positioned that the latter and their weights d^{14} , when the mechanism is stationary, tilt forward against the pinion-sleeve d^8 , as illustrated in Fig. 11. When, however, the shaft is operated by the spring and the pinion d^3 and pinion-sleeve d^8 are being rotated, the weights d^{14} will be thrown out by centrifugal force, and the lower face of the finger d^{16} and the upper surface of the ring d^{10} will separate, so as to bring said parts respectively in engagement with the friction-ring r and the washer r^2 , which will control the movement of the pinion-sleeve d^8 , checking the rapidity of its rotation and causing it and the parts connected therewith to move slowly at any predetermined speed, depending upon the position and power of the governor-weights d^{14} selected.

r^3 is a washer arranged between the cap portion f of the casing and the friction-ring r . The washers $r^2 r^3$ may be formed of rubber, leather, or any composition that is desirable, and if it is found to be necessary the ring r may be connected to the ring d^{10} , so as to turn therewith, provisions being made, however, to move one ring relatively to the other. The pin-

ion-sleeved d^8 is slightly elongated, so that it may have a limited sliding movement, heretofore referred to, relatively to its driving-gear d^6 .

The mechanism is so constructed that it 5 may be employed with the door opening in either direction. In Figs. 4 and 6 I have shown the spring v and the dog z as being arranged for the checking of the door, which is opened in one direction, and in Figs. 5 and 10 7 I have shown these parts as being reversed for operating a door opening in the opposite direction. The dog z , which co-operates with the ratchet j , is double-headed, so that it too may operate in either direction. In practice 15 the dogs z and z , as well as the spring v , should be each stamped with the symbols "R" and "L," indicating "right" and "left," respectively, or some other character of similar import, so that when the mechanism is 20 put together, if it is desired to operate the door opening to the right, then these parts should be placed in a case with their sides bearing the inscription "R" facing up, or vice versa.

25 For the purpose of keeping the mechanism well oiled, in the cap f is formed an oil-well f^3 below the shaft g , the latter being formed with an axial aperture g^3 , connected by radial apertures g^4 , leading to the surface of the 30 shaft at various points, to conduct the oil led up through the shaft by the wick g^5 to the points that it is desirable should be kept oiled. By means of these oil-ducts the movable parts are kept well oiled, so as to move 35 noiselessly and with minimum resistance.

d^{18} represents a coiled spring arranged in an aperture d^{19} of the arms d^9 and bearing against the side of the arm d^{12} .

d^{20} represents a screw arranged in the aperture d^{19} , adapted to press against the spring d^{18} , regulating the force with which said spring shall bear against the arms d^{12} . The pressure of the spring upon the arms of the weights is such as to allow the weights to move 45 to operate the friction, but is sufficient to hold said weights against inoperative movements or vibrations that might cause rattling. The spring d^{18} should be placed as near as possible to the pivot-pin d^{15} , so as to interfere but 50 slightly with the proper movements of the weights.

The operation of the parts just described is as follows: Assuming the door to be closed, as shown in full lines in Fig. 2, the opening 55 of the same will be accompanied by the following movements: The lever m , turnbuckle m' , and rod n' , through the medium of the dog and ratchet-wheel j , will cause a rotation of the sleeve i and a consequent widening up 60 of the spring v . The shaft g is rotated with the sleeve; but the dog z , carried thereby, rides easily over the internal teeth d' of the wheel d until the door is opened to the desired extent. As soon as the door is released 65 it is free to swing to its closed position, the spring by virtue of the power stored up in the opening of the door begins to unwind and

in doing so reverses the operations above described, rotating the shaft g and causing the door to move to a closed position. The rotation of the shaft g by the spring causes the dog z to firmly engage the internal teeth of the ratchet-wheel d , which, through the medium of the connecting gearing, rapidly rotates the pinion-sleeve d^8 and its ring d^{10} . This movement of the ring and pinion-sleeve causes the governor or controlling weights d^{14} to be thrown outward by centrifugal action, forcing the frictional members into engagement with each other, which checks the movement 80 of the door and causes it to close slowly without jarring or slamming. If the door tends to swing too rapidly, the action of the weights is to increase the friction and check the door. In all cases the action of the weights causes 85 sufficient friction to control the door and prevent its moving except at a predetermined speed. The more rapidly the door tends to swing to its closed position the greater will be the force with which the governor-weights 90 are thrown outward and the greater will be the friction produced to check the door. It follows, therefore, that by my invention the amount of resistance to be offered to the action of the door is automatically regulated, 95 requiring no adjustment for different sizes or weights of the doors.

In Figs. 18 to 25 are illustrated another means for connecting the dog z to the wheel d , and also another form of governor-weights 100 and friction devices.

Referring to Figs. 18 and 19, it will be seen that the internal teeth of the wheel d are dispensed with, and in place of said teeth and the serrations on the dog z I employ a divided 105 ring z^1 , arranged in an annular depression in the wheel d and adapted to engage the flange z^5 upon said wheel. The free end of the dog z is arranged between the ends z^6 z^7 of the divided ring. One end of the dog is beveled, 110 as at z^8 , and on the opposite side of the dog is formed a depression z^9 . When the shaft g is rotated in the direction of the arrow in Fig. 18, corresponding to the opening of the door, the collar y engages the dog on the side 115 opposite to the depression z^9 , causing the unbeveled side of the dog to engage the end z^6 of the ring. This movement causes the dog to assume a radial position, resulting in the turning of the ring in its seat without causing sufficient friction between the ring and the flange z^5 to clutch said parts together. When, however, the shaft g is rotated by 120 means of the spring, the collar y carries one side of the pawl z into engagement with the end z^7 of the ring, the further movement of the collar y causing the pawl z to turn in its bearings to the position shown in Fig. 19, the depression z^9 permitting this movement. In 125 this position of the pawl z the further movement of the collar y causes the pawl to act as a lever to spread the ring to clamp the ring and wheel d together, thus causing said wheel to move with the shaft g , as in Fig. 6.

Referring to Figs. 20, 21, and 22, the sleeve-pinion d^8 instead of the arms d^9 is formed with two laterally-projecting flanges d^{10} . To each of these flanges is pivoted a governor-weight d^{11} , adapted by the rotation of the shaft g to be thrown outward in the direction of the arrows. d^{13} represents brake-shoes, each pivoted to one of the flanges d^{10} and carrying a friction-pad d^{14} , adapted to engage the wall of the casing. Springs d^{15} normally hold the shoes, with their pads, out of engagement with the wall of the casing. Parts d^{16} , carried by the shoes, are arranged in a position to be engaged by the governor-weights d^{11} . If now the door be open and left to be closed by the action of the spring v , the governor-weights will cause the friction devices or shoes d^{13} , with their pads, to be thrown outward, the latter engaging the wall of the casing to check the action of the door when the latter moves beyond the predetermined speed. Springs d^{17} , engaging the governor-weights at a pivotal point, serve to check any rattling movement of the weights, as in the case of the springs d^{18} in Fig. 16.

In Figs. 23, 24, and 25 the governor-weights d^{30} are pivoted to a flange d^{31} on the sleeve-pinion d^8 , so that they will move in opposite directions on their pivotal points instead of being arranged as in Fig. 20, where they move in the same direction. A spring d^{32} serves to draw the governor-weights toward the pinion-sleeve d^8 and the brake-shoe d^{33} out of engagement with the wall of the casing when the pinion is not rotating or when it is rotating at a predetermined speed. In the form shown in Figs. 23, 24, and 25 the rotation of the pinion-sleeve d^8 causes the governor-weights to move outward in the direction of the arrow. When this rotation is beyond a predetermined speed, the governor-weights will be thrown out with sufficient force to cause their brake-shoes to engage the wall of the casing or some other supplemental friction part, checking the action of the spring and door, as in the other cases. By having the governor-weights arranged as in Fig. 23 I am enabled to dispense with the parts for preventing rattling. Suppose the parts to be arranged as in Fig. 23 and the pinion-sleeve d^8 turning in the direction opposite to the hands of a watch, as in Fig. 19. To close the door, the brake-shoes d^{33} will engage the walls of the casing, but in a different manner. The casing or supplemental part engaging the brake-shoe at the right tends to force said brake-shoe inwardly, while the casing or supplemental friction part engaging the brake-shoe at the left operates as a drag on said shoe and tends to force said shoe outward, thus aiding the action of the governor-weights. This arrangement here shown is especially advantageous. It provides for the arrangement of the shoes that act alike, whether the door opens to the right or to the left. The construction is simple, permitting the parts to be made of rough castings, thus eliminat-

ing the cost of finishing, &c. The position of the pivots above the weights d^{30} in Fig. 23 may be varied as desired. The nearer they are placed toward the pinion-sleeve d^8 the greater will be the resistance produced by the drag between the friction-pad and the wall of the casing or the more will the force of the governor-weights be augmented. 75

It will be observed that in all cases the governor-weights automatically regulate the resistance offered to the driving action of the spring for the closing of the door and increasing said resistance in direct proportion as the speed of the door increases, thereby causing the door to close with an easy steady movement. 80

Various modifications of my invention may be made without departing from the spirit and scope thereof, which comprises an automatic mechanical door-check in which the parts are so arranged that they automatically regulate the resistance offered to oppose the closing movement of the door. 90

Having now explained the nature of my invention and described a way of constructing and using the same, though without attempting to set forth all of the forms in which it may be made or all of the modes of its use, what I claim, and desire to secure by Letters Patent, is—

1. A door-check comprising a spring, a shaft operated thereby, a centrifugal regulating device, and a reversible connection between said shaft and said device. 100

2. A door-check comprising a shaft, a spring, arranged to rotate said shaft in one direction, governor-weights mounted concentrically on said shaft but loose relative thereto, and means for intermittently connecting the shaft with said weights, in combination with friction devices operated by said weights. 105

3. A door-check comprising a casing, a spring, a shaft adapted to be driven by said spring, mechanical friction devices, means for connecting said devices with the shaft when the door is being closed, and means for preventing the rattling of said devices. 110

4. A door-check comprising a shaft, a spring arranged to operate the latter, a resistance, centrifugal means for operating said resistance, and a reversible dog interposed between said means and said shaft. 115

5. A door-check comprising a shaft, a reversible spring arranged to operate the latter, a resistance, centrifugal devices arranged to operate said resistance, connections between said shaft and devices comprising a reversible intermittently-acting means. 120

In testimony whereof I have signed my name to this specification, in the presence of two subscribing witnesses, this 21st day of August, A. D. 1896. 125

EUGENE I. BLOUNT.
